No. 1605. George S. Morris design or design. Inventor.

Patented Jan. 17, 1862.

Des 1608

George B. Owen, of New York, N.Y.
Letters Patent No. 1608, dated June 17, 1862.

The schedule referred to in these Letters Patent and making part of the same.

To all whom it may concern:

Be it known that I, George B. Owen, of the City of New York, have invented a new and original Design, for a Clock Case; and I do hereby declare that the following is a full, clear and exact description of the same, reference being had to the accompanying drawings, making a part of this specification, in which

Figure 1, is a face or front view of a clock case of my design.

Figure 2, a side view of the same.

Figure 3, a horizontal section of the same, taken in the line x. x. Figure 1.

Similar letters of reference indicate corresponding parts in the several Figures.

The case A, is of quadrilateral form and is placed upon a rectangular base B, which is surrounded by an inverted oval a, the latter encompassing the lower part of the case at its front and sides.

46

Des. 1608

The front corners of the case A, have plane surfaces b, the greater portion of their length, and each surface b, has a semi cylindrical projection c. The upper ends of the plane surfaces b, are connected with the upper parts of the corners of the case, by cyma rectas d, and the lower ends of said surfaces are connected with the lower parts of the corners of the case by ovols e.

C, is the cap of the case which is formed by a fillet f, a torus g, scotia h, and a torus i, the latter being surmounted by a fillet j.

The mouldings of the cap C, like the ovols e, of the base extend across the front of the case and around the sides, the latter being shown in Figure 2.

The front of the case is formed of a panel k, which leaves a pilaster or projection l, at each side on which the plane surfaces b, and semi cylindrical projections c, are formed, see Figures 1 and 3.

Having thus described my invention, what I claim as new and desire to secure by Letters Patent, is,

The general configuration of the parts, as shown and described, to form a new and original Design for a Clock Base.

Witnessed,

es.s.
